(57) **CLAIM**

The ornamental design for an adapter for a tracheal tube, as shown and described.

DESCRIPTION

FIG. 1 is a top view of an adapter for a tracheal tube; FIG. 2 is a front view of the adapter for a tracheal tube; FIG. 3 is a bottom view of the adapter for a tracheal tube; FIG. 4 is a side view from the left side of the adapter for a tracheal tube; FIG. 5 is a back view of the adapter for a tracheal tube; FIG. 6 is a side view from the right side of the adapter for a tracheal tube; FIG. 7 is a perspective view from the top of the adapter for a tracheal tube; and, FIG. 8 is a perspective view from the bottom of the adapter for a tracheal tube. The broken lines in the drawings illustrate portions of the adapter for a tracheal tube which forms no part of the claimed design.

1 Claim, 8 Drawing Sheets
